RESEALER FOR A CAN OR THE LIKE

Major E. Weber, R.R. 5, Brookville, Ind. 47012

Filed May 20, 1969, Ser. No. 17,240

Term of patent 14 years

Int. Cl. D9—02

U.S. Cl. D9—281

Fig. 1

Fig. 2

Fig. 3

Fig. 4

Fig. 5

Fig. 6

FIG. 1 is a top plan view of a resealer for a can or the like showing my new design;

FIG. 2 is a bottom plan view thereof;

FIG. 3 is a side elevational view thereof, the opposite side being a mirror image thereof;

FIG. 4 is a rear elevational view thereof;

FIG. 5 is a front elevational view thereof; and

FIG. 6 is a sectional view taken along the line 6—6 in FIG. 1.

I claim:

The ornamental design for a resealer for a can or the like, substantially as shown and described.
